UNITED STATES PATENT AND TRADEMARK OFFICE
Certificate

Patent No. D. 426,380

Patented: June 13, 2000

On petition requesting issuance of a certificate for correction of inventorship pursuant to 35 U.S.C. 256, it has been found that the above identified patent, through error and without any deceptive intent, improperly sets forth the inventorship.

Accordingly, it is hereby certified that the correct inventorship of this patent is: Irit Dar, Fair Lawn, NJ (US); Martha Davis, San Francisco, CA (US); and Andrea Ruggiero, NY (US).

Signed and Sealed this Eighteenth Day of June 2013.
